FRED F. MAIN, OF CHICAGO, ILLINOIS, ASSIGNOR OF ONE-TENTH TO UNDERWOOD
TYPEWRITER COMPANY, OF NEW YORK, N. Y., A CORPORATION OF DELAWARE.

TYPE-WRITER AND COMPUTING-MACHINE.

1,151,492.

Specification of Letters Patent. Patented Aug. 24, 1915.

Application filed December 14, 1911. Serial No. 665,781.

To all whom it may concern:

Be it known that I, FRED F. MAIN, a citizen of the United States, residing at Chicago, in the county of Cook and State of Illinois, have invented new and useful Improvements in Type-Writers and Computing-Machines, of which the following is a specification.

This invention relates to typewriting machines, and particularly to means for locating perforated sheets in the machine in position to be written upon, and for also feeding the sheets in line-space direction.

I am aware of an application filed by Lyman R. Roberts, December 23, 1909, No. 534,579, to the overlapping subject-matter of which and the present application, I make no claim.

In the usual operation of typewriting, a number of sheets may be placed in the machine with their leading edges in register. The work-sheets with their carbons are imposed one upon another to form a sheaf, which is introduced into the machine; and after the writing is done, all the sheets must be removed in order to permit the top sheet, usually a bill, to be withdrawn and replaced by a fresh blank, whereupon the sheaf may be replaced in the machine.

In bookkeeping and similar work, however, it is desired to retain in the machine a record sheet, that is, a sheet upon which are made successive records of the items written upon bills or other temporary work-sheets which are written upon and then removed while the record sheet remains; the entries appearing in their proper places on the bills, while the same entries appear one after another in proper sequence on the record or permanent sheet. In performing this class of work, it is desired to make several copies simultaneously, by means of carbons or ribbons, or both, upon two or more sheets; and it is also desired to place the upper or outer temporary sheet or sheets in the machine in position to insure that the typewriting shall fall in the proper positions on said sheets, as well as in proper position beneath the last written line on the permanent or record sheet.

In practising my invention, the sheets will be superposed in different positions in the machine, usually with the sheets overlapping one another at their top, bottom and

side margins in different ways. The position of each sheet in the machine is determined by a printing-line on said sheet; this printing-line being sometimes indicated by a ruling, which is placed upon the work-sheet prior to being written upon. Where different kinds of forms are used, the ruled line of one sheet which is to receive a certain typewritten line, may be in an entirely different position from the ruled line on another sheet which is to receive the typewritten impressions at the same time; and both of said ruled lines may be differently located from the printing-line on the record sheet which is in the machine. This is all taken care of by perforating the work-sheets in their margins, and providing upon the typewriting machine adjacent to the revolute platen a series of studs upon which the work-sheets may be positioned or gaged by means of their marginal perforations. These studs are preferably arranged along the right and left-hand sides of a work table or support adjacent to the revolute platen, so that any sheet may be adjusted up or down as required and without disturbing the adjustment of a sheet previously placed upon the studs. By this means not only are sheets properly placed in relation one to another, so that the typewriting may fall upon the various places required upon the sheets, but the sheets are also positioned or gaged with reference to the printing line on the platen, that is, the line along which the types strike in the typewriting machine.

One of the features of the present invention is the provision of a work support in connection with the revolute platen of a typewriting or computing machine, to facilitate the assembly of sheets in their proper order and positions.

In using my invention, very many work-sheets, all having various sizes and characteristics, may be equally and accurately brought into printing positions upon a revolute platen in their required relationship to one another.

Another feature of my invention resides in the provision of means whereby not only one but several superimposed or otherwise arranged record sheets may remain in the machine in proper relationship to one another and to the revolute platen, while bills or temporary work sheets are suc-

sively inserted and withdrawn, so that the successive records may appear on all the record sheets. This is accomplished in such a way that the record sheets are permitted 5 to have different characteristics as to size, etc.; and the several record sheets may occupy unlike positions. Any one or more of several sheets may be removed from the machine while leaving another sheet properly retained in the machine, even if said 10 undisturbed sheet may be a top sheet.

I arrange at what is usually termed the delivery side of the platen, a work support having a flat surface for convenience in arranging the work sheets. This support preferably inclines from the platen upwardly and rearwardly, and may have an area somewhat in excess of the largest work-sheet to be used. Any sheet when placed 20 upon this support may engage, by means of the perforations with which the sheet is first provided, projecting studs, of which there is an array preferably on each side of the work support.

25 The sheets may be superposed in various relationships, with carbons between and the studs not only enable the sheets to be placed in the proper relationship one to another, but also gage or position the sheets 30 properly relatively to the printing line on the platen; the studs being connected to the platen for this purpose by being arranged upon one or more endless flexible bands running around the end portions of the 35 platen and extending up along said work support, and then running over a roll and down to the platen again. The bands may have any required length, and the work support may be of any required height or extent. The upper strands of the bands may 40 lie upon the flat surface of the work support. The studs not only serve to engage and position the sheets when they are laid upon said support, but they are also employed to carry the sheet or sheets around 45 the cylindrical platen to proper position to be written upon. These stud devices serve as the means for line-spacing the sheets, which it will be understood do not 50 need to be manipulated or skewed about in the manner usual when inserting and adjusting a sheet in a typewriting machine, for bringing a ruled line on the sheet into parallelism with the writing line on the 55 platen, since this registry of the sheet is taken care of by the studs. Any sheet that is impaled upon the studs, is necessarily parallel with the cylindrical platen, without further attention from the operator; 60 and the usual releasable pressure roll mechanism may be omitted.

65 It will be understood that when the sheets are assembled or collated on the said flat surface, with the sheet perforations engaging the line-spacing studs in such a manner

that the desired various ruled or printed lines on the several sheets are registered properly with one another, the platen may be revolved forwardly, and the sheets, which are connected to the platen by means of the endless bands, are carried around the idle roll, and down back of and beneath the platen, and up to proper position for receiving the type impressions; the types usually striking 70 upon the front of the platen.

75 In the accompanying drawing, the revolute platen 2 is mounted on the carriage frame 1, and is rotatable by means of a line-space lever 3, which it will be seen has a pawl 3^a to drive a ratchet wheel 3^b, the latter mounted as usual on the end of the platen to rotate the same; this intermittent line-spacing mechanism being of usual construction.

80 The work sheets, which are of various sizes are designated as 18, 19, 20, and each sheet has along a side margin perforations 20^a, to engage gaging, spacing and attaching means shown in the form of projecting gage studs 12. By the term "studs", I do 85 not wish to limit myself to a specific form, but desire to include equivalent forms of attaching or spacing means, or both. The studs enable the justifying or gaging of a number of different sheets with respect to 90 each other and the lines thereof which will come to the printing point at the same time. The work sheets are laid one at a time upon a work support 9, which is in the form of a flat surfaced plate extending upwardly and rearwardly from the delivery side of 95 the platen, that is, the side from which the sheets usually emerge from the machine; and said plate is supported by standards 8 which rise from the rear of the carriage; upper and lower brackets 8^b connecting the plate 9 to the standards 8. Said studs may 100 be carried by one of the flexible endless bands 4, 4, and the bands may run around the opposite ends of the platen 2, the latter 105 having its ends reduced to receive the bands, so that the latter may lie flush with or not protruded above the printing surface of the platen, as shown, so that they may not foul with the edges of the work sheets. These bands run over an idle roll 5 which is 110 placed above and behind the work support 9; the roll 5 also having reduced ends to receive the bands.

115 As many studs may be arranged upon the bands as desired, and they may be equally spaced, as shown, to match the perforations in the work sheet.

120 Proper relationship between the opposite sides of the studs is assured by means of gears 6, fixed to the ends of a horizontal shaft 7, parallel with the roll 5 and platen 2. These gears rotate in unison and mesh 125 with the studs 12, whereby accurate relationship of the studs along one side to those 130

along the other side of the work table is assured; creeping of either band being prevented.

The work sheets or forms are assembled 5 individually and independently on the line-spacing studs 12 of the various bands, in such a manner that each sheet shall present to the printing position such part as is to receive the type impressions. The writing 10 is done in multiple, since carbon sheets, ribbons, or other duplicating means are assembled between the work sheets. The larger work sheet 18 may be placed in position first, and may remain permanently in the 15 machine until it is filled with writing, which of course would consist of carbon impressions of the typewriting on the superposed sheets 19, 20. The sheet 18 may have perforations only along its right-hand margin, 20 whereby it may be held upon and gaged by means of the right-hand studs 12. The sheets 19 and 20 may have perforations only upon their left-hand margins. 20 may be a bill, and may receive the primary impressions 25 directly from the types of the typewriter; and 19 may be a shipping order, or any other form upon which it is desired to enter the item in correspondence with the entry upon the bill or other individual sheet 30 20. Of course any desired number of sheets and blanks of any desired kinds may be employed simultaneously.

Any work sheet when laid upon the table 9, may engage by means of its perforations 35 the studs 12, at either one or both sides of the table 9, and the projecting studs will cooperate with the perforations in the sheets to control the positions of the latter relatively to the printing point or line on the 40 platen 2. After the sheets are assembled, a handle or crank 16 may be grasped to rotate a large gear wheel 14, which is mounted upon a stud 15 projecting from a bracket 13, and meshes with a small pinion 17 which 45 is fixed upon the end of the platen shaft, whereby the platen is rotated and the bands set in motion. The gear 14 being revolved in counterclockwise direction, the platen is rotated in line-spacing direction, and the 50 studded bands carry the assembled sheets up around over the idle roll 5, and down behind the work support or table 9, and under the platen and around up in front of the same, to bring the sheets to the printing 55 point, or to position to receive the line of type impressions. By means of the large or movement-multiplying gear 14, the platen is caused to revolve rapidly, and the forms are quickly brought into position. If desired, 60 the usual sheet-feeding mechanism may be retained, and sheets be carried by the studs between the platen and these usual feeding devices. However, the studs alone may be relied upon to advance the sheets 65 around the platen line by line, and hence

the ordinary sheet-feeding devices need not always be used. The sheets, it will be seen, come up in front of the platen in the usual way, into position to receive the first line of type impressions.

To guard against the forms falling off from the studs as they descend behind the work table 9, there is provided a metal sheet or guard 10, which curves forwardly at its upper end to form a hood or guiding apron 70 75 10^a over the roll 5, and also curves at its lower end around the platen and extends up in front thereof at 10^b, nearly to the usual printing line as illustrated. This guard 10^a, 10^b assures that the sheets shall remain 80 in position upon the studs, so that there is no liability of displacing the sheets. The guard 10 may be supported upon a bracket 11.

After the type impressions are made, one 85 or more sheets may be removed while another sheet or sheets remain in the machine. For instance, the right-hand sheet 18, which is the bottom sheet, could be removed without disturbing either 19 or 20. Or top sheet 90 19 could be removed without disturbing 20 or 18. Or both 19 and 20 could be removed without disturbing 18. The individual forms or accounts on the sheets 19, 20, may hence be removed while the record sheet 18 95 remains in the machine. In some cases, a single item is written upon the sheets 19 and 20, whereupon they are removed, and fresh blanks inserted, but at a lower point upon the table 9, so that subsequently the 100 typewritten impressions made upon these fresh blanks will fall at a lower place on the record sheet 18 than the previously typed impressions. These successive individual sheets will receive individual lines 105 of type impressions, which fall one below another upon the record sheet 18, although these type impressions all appear in the same place upon the individual sheets. Although the individual sheet may always 110 have writing on the same line, still the record sheets will never have successive entries made on the same line. It is this necessity for unlike and irregular relationship of the different sheets at successive operations, 115 that makes it impracticable to assemble forms properly for this kind of work in the usual construction of revoluble-platen typewriting machine.

When the typewriting of a line is completed, the platen may be rotated forwardly in the usual manner, and the forms may be all brought to assembling position, where the individual forms may be withdrawn and new forms inserted as required.

This device is especially adapted to be used in typewriting machines which are used for writing on sheets that are punched at certain places. Such sheets are used in bookkeeping, particularly with loose-leaf 125 130

ledgers and other record books, and the writing on such loose leaves is usually made as a carbon copy of the original bill. In assembling such work on my device, it will be noted that the loose sheet which is to receive the carbon copy, will be laid first on the assembling surface 9, then on top of this will be placed the carbon sheet, and on top of this will be placed the bill which is to be sent to the customer. Any other forms such as shipping order slips may also be positioned either in back or on top of the bill itself. Thus the sheet on which records are to be kept lies next to the assembling table.

If then said bill and loose leaf are carried by the belts 4 around the platen, it will be seen that when the bill is in position to be removed, the loose leaf of the journal will lie flat on the assembling surface and the bill form may be removed without disturbing the loose leaf. Then another bill form may be inserted without removing the loose leaf from the mechanism, and if the pins 12 are at line-space intervals, said second sheet may be rapidly inserted at any desired line space. To put it in another way,—after one form has been written on and passed around the platen and then removed, the loose leaf lies in position on the assembling table in convenient position to place another form on the pins 12 over the loose leaf, and said pins form a convenient means for locating said second form at such a number of line spaces from the carbon record of the first form as may be desired.

Variations may be resorted to within the scope of the invention, and portions of the improvements may be used without others.

Having thus described my invention, what I claim and desire to secure by Letters Patent is:

1. In a typewriting machine, the combination with a traveling carriage and a platen rotatably mounted therein, of a belt at one end of said platen, said platen having a reduced section which said belt encircles, a support on said carriage, a pulley on said support, studs on said belt, an adjusting table adjacent to which said belt passes, and a shield encircling said pulley extending down the rear side of said table and beneath the platen to hold a work-sheet in position as it is engaged by said studs.

2. In a typewriting machine, the combination with a traveling carriage and a platen rotatably mounted therein, of an adjusting table extending upwardly and rearwardly from said platen, a belt passing over said adjusting table and around said platen, a pulley at the upper end of said table around which said belt passes, studs on said belt adapted to engage corresponding openings

in a work-sheet, and a shield encircling said pulley and extending downwardly behind said adjusting table for holding a work-sheet as it is fed toward the platen.

3. In a typewriting machine, the combination with a traveling carriage and a platen rotatably mounted therein, of a support extending from said carriage, a pulley on said support, a belt passing round said platen and said pulley, studs on said belt adapted to engage corresponding openings in a work-sheet, an assembling table on said carriage on which work-sheets may be assembled to said studs, and a shield at the rear side of said table for holding a work-sheet in place as it is carried behind said table toward the platen.

4. In a typewriting machine, the combination with a traveling carriage and a platen rotatably mounted therein, of a support extending from said carriage, a pulley on said support, belts encircling said platen and said pulley, studs on said belts adapted to enter corresponding openings in a work-sheet, and means for holding the studs of both of said belts in alinement.

5. In a typewriting machine, the combination with a traveling carriage and a platen rotatably mounted therein, of a support extending upwardly and rearwardly from said carriage, a pulley on said support, a belt encircling said platen and said pulley, a line-space mechanism for said platen, studs on said belt set at line-space intervals, and a sheet-adjusting table along which said belt runs.

6. In a typewriting machine, the combination with a traveling carriage and a platen rotatably mounted therein, of a support on said carriage extending upwardly and rearwardly therefrom, an assembling surface on said support, an endless belt encircling said platen and traveling past said assembling surface, a shield encircling the upper end of said belt and passing downwardly along the return reach of said belt toward the platen and encircling said platen, and a line-space mechanism for said platen.

7. In a typewriting machine, the combination with a traveling carriage and a platen rotatably mounted therein, of a line-space mechanism for said platen, a belt, extending from each end of said platen, an idle pulley for said belts, means for causing said belts to move synchronously, studs on said belts to engage perforations in the side edges of the sheet, and a sheet-adjusting table along which said belts run.

8. In a typewriting machine, the combination with a traveling carriage and a platen rotatably mounted therein, of means for turning said platen, a support extending upwardly and rearwardly from said carriage, an idle pulley, belts encircling said

platen and said idle pulley, studs on said belts, gear wheels engaging said studs, and means to cause the gear wheels to rotate in unison.

9. In a typewriting machine, the combination with a traveling carriage and a platen rotatably mounted therein, of a support extending upwardly and rearwardly from said carriage, a belt encircling said platen and extending along said support, studs on 10 said belt on which a work-sheet may be impaled, and a shield adjacent to the return stretch of said belt to hold paper impaled on said studs in place.

10. The combination with a revoluble 15 platen, of two series of studs, one at each end of the platen, upon which the work-sheet may be positioned by means of marginal perforations, and means to cause said sets of studs to move in unison with said 20 platen and with each other.

11. The combination with a revoluble platen, of two series of studs, mounted one at each end of the platen, upon which the work-sheet may be positioned by means of 25 marginal perforations, each of said sets of studs extending away from said platen, and one set being parallel with the other set, and means for rotating the platen and simultaneously moving said sets of studs in 30 unison toward or away from said platen.

12. The combination with a revoluble platen, of a series of studs upon which works-sheets may be variously positioned by means of marginal perforations, and 35 feeding means for bringing the sheets *en bloc* in the order disposed on said studs.

13. The combination with a revoluble platen, of a series of studs upon which worksheets may be positioned by means of marginal perforations, said series of studs extending away from said platen, and means 40 for making said studs travel in unison with the rotation of the platen.

14. The combination of a revoluble 45 platen, a work-supporting table extending away from the platen, a series of studs engageable by a sheet laid upon said work table, and arranged to engage perforations in the side margin of the work-sheet, and means 50 for rotating the platen and simultaneously moving said series of studs.

15. The combination of a revoluble platen, a work-supporting table extending away 55 from the platen, a series of studs engageable by a sheet laid upon said work table, and arranged to engage perforations in the side margin of the work-sheet, said series of studs extending along the side of said work table, and means for rotating the platen, and 60 simultaneously moving said series of studs.

16. The combination of a revoluble platen, a work-supporting table extending away 65 from the platen, a series of studs engageable by a sheet laid upon said work table, and

arranged to engage perforations in the side 65 margin of the work-sheet, said series of studs extending along the side of the work table, a second series of studs corresponding with the first, and extending along the opposite side of said work table to be engaged 70 by perforations in the other side margins of the work-sheet or sheets, and means for rotating said platen and simultaneously advancing all of said studs.

17. The combination of a revoluble platen, 75 a work-supporting table extending away from the platen, a series of studs engageable by a sheet laid upon said work table, and arranged to engage perforations in the side margin of the work-sheet, said series of 80 studs extending along the side of said work table, and means for causing said studs to move in unison with the rotation of said platen.

18. The combination of a revoluble platen, 85 a work-supporting table extending away from the platen, a series of studs engageable by a sheet laid upon said work table, and arranged to engage perforations in the side margin of the work-sheet, said series of 90 studs extending along the side of the work table, a second series of studs corresponding with the first, and extending along the opposite side of said work table, to be engaged 95 by perforations in the other side margins of the work sheet or sheets, and feeding means for positioning said sheets on said platen in the order and position they were arranged on said studs.

19. The combination of a revoluble platen, 100 a work-supporting table extending away from the platen, a series of studs engageable by a sheet laid upon said work table, and arranged to engage perforations in the side margin of the work-sheet, said series of 105 studs extending along the side of the work table, a second series of studs corresponding with the first, and extending along the opposite side of said work table to be engaged 110 by perforations in the other side margins of the work-sheet or sheets, bands on which said studs are carried, said bands running around the ends of the platen, and means to coöperate with the platen to support the bands.

20. The combination of a revoluble platen, 115 a work-supporting table extending away from the platen, a series of studs engageable by a sheet laid upon said work table, and arranged to engage perforations in the side 120 margin of the work-sheet, said series of studs extending along the side of said work table, a second series of studs corresponding with the first, and extending along the opposite side of said work table to be engaged 125 by perforations in the other side margins of the work-sheet or sheets, bands on which said studs are carried, said bands running

around the ends of the platen, and means to coöperate with the platen to support the bands, controlling means being provided for causing the bands to travel in unison with each other.

21. The combination of a revoluble platen, a work-supporting table extending away from the platen, a series of studs engageable by a sheet laid upon said work table, and 5 arranged to engage perforations in the side margin of the work-sheet, said series of studs extending along the side of the work table, a second series of studs corresponding with the first, and extending along the opposite 10 side of said work table to be engaged by perforations in the other side margins of the work-sheet or sheets, bands on which said studs are carried, said bands running around the ends of the platen, and means to 15 coöperate with the platen to support the bands, means being provided to engage the studs on the bands, to insure proper registry of the studs.

22. In a typewriting machine, the combination with a work-sheet support or table, 25 of a row of impaling gage-studs extending along said support or table, for positioning a perforated work-sheet with reference to the printing line by means of perforations 30 in the work-sheet, a revoluble platen adjacent to said support, and an endless band to coöperate with said studs for advancing the work-sheet.

23. In a typewriting machine, the combination with a revoluble platen, of a work-sheet table adjacent to the platen and arranged at the delivery side thereof, a row of gage-studs extending along said table upon which a perforated work-sheet is impaled, said gage-studs arranged to gage the 35 work-sheet by means of its perforations relatively to the printing line on the platen, and an endless band to coöperate with said studs for advancing the work-sheet.

45 24. In a typewriting machine, the combination with a revoluble platen, of a pair of sheet-gaging devices for positioning perforated work-sheets relatively to the printing line on the platen, each of said sheet-gaging devices consisting of a set of studs upon 50 which work-sheets may be impaled by means of perforations in the side margins thereof, said sheet gaging devices arranged at right angles to the platen, and means to advance 55 said sheet-gaging devices and simultaneously rotate the platen.

25. In a typewriting machine, the combination with a revoluble platen, of a work-sheet support adjacent to the platen and extending away therefrom, and sets of gage 60 studs extending away from the platen, each set at right angles to the platen and upon which the side margins of the work-sheets may be impaled, said gage studs arranged 65 to position the work-sheet relatively to the

printing line on the platen, said sets of gage studs movable along said support to carry the sheets to and from the platen.

26. In a typewriting machine, the combination with a revoluble platen, of a work-sheet support adjacent to the platen and extending away therefrom, sets of gage studs 70 extending away from the platen, each set at right angles to the platen and upon which the side margins of the work-sheets may be 75 impaled, said gage studs arranged to position the work-sheet relatively to the printing line on the platen, an endless band to connect said studs with the platen, and line-spacing mechanism.

27. In a type-writing machine, the combination with a work-sheet support and a revoluble platen, of two sets of impaling gage studs projecting from said support for positioning work-sheets perforated in their 85 side margins, each of said sets extending away from the platen and at right angles thereto, and movable to and from the platen.

28. In a typewriting machine, the combination with a revoluble platen, of two sets of work-sheet impaling studs, each set extending away from the platen and acting in conjunction with the platen to bring to writing position work-sheets perforated 95 along their side margins, for impaling on the studs.

29. In a typewriting machine, the combination with a revoluble platen, of two sets of work-sheet impaling studs, each set extending away from the platen and acting in conjunction with the platen to carry to, around and away from the platen work-sheets perforated along their side margins, 100 for impaling on the studs.

30. In a typewriting machine, the combination with a revoluble platen, of a work-sheet support adjacent to the platen and extending away therefrom at the delivery side thereof, and two sets of gage studs at 110 the sides, one set at each side of said support, said gage studs engageable by perforations in the side margins of work-sheets laid upon said support, said gage studs arranged to gage the work sheet by means of 115 such perforations, relatively to the printing line on the platen, and movable to carry the sheets to and from the platen.

31. The combination with a revoluble platen, of a device provided with studs upon which the work-sheets are impaled, said studded device extending away from the platen, means for moving the studded device to carry the sheets over the platen, and means to retain the work-sheet on the studs, 120 said retaining means in the form of a guard plate which extends to and partly around the platen.

32. The combination of a revoluble platen, an idler, and a studded device extending 125

from said platen to said idler for impaling and advancing work-sheets around the platen in a predetermined relation.

33. The combination of a revoluble platen, 5 an idler, a studded device extending from said platen to said idler for impaling and advancing work-sheets, and a guard extending from said platen to said idler and curving or extending around both of them for 10 retaining the work-sheet on the studded device.

34. The combination of a revoluble platen, a work support extending from the platen, a studded sheet-carrying device 15 comprising two endless bands, and an idler over which the bands run.

35. The combination of a revoluble platen, a work-support extending from the platen, a studded sheet-carrying device 20 comprising two bands, an idler over which the bands run, a sheet guide extending from the platen to the idler and curving around both thereof, and means for causing said bands to run in unison.

36. The combination of a revoluble platen, a work-support extending from the platen, a studded sheet-carrying device comprising two bands, an idler over which 30 the bands run, a sheet guide extending from the platen to the idler and curving around both thereof, and sprocket-wheels or gears to engage the studs on both bands to cause them to run in unison.

37. The combination of a revoluble platen, 35 a work-supporting table extending away from the platen, a series of studs engageable by a sheet laid upon said work table, and arranged to engage perforations in the side margin of the work-sheet, said series of 40 studs extending along the side of the work table, a second series of studs corresponding with the first, and extending along the opposite side of said work table to be engaged by perforations in the other side margins 45 of the work-sheet or sheets, and a movement-multiplying gearing to rotate the platen and drive said studs.

38. The combination of a revoluble platen, 50 bands extending from said platen and having studs for carrying work-sheets, a co-operating device over which the bands run, and a sheet guard extending from said co-operating device to the platen, and curving around the platen nearly to the printing line thereof.

39. In a typewriting machine, the combination with a platen, of a work-sheet support adjacent to the platen, and parallel sets 55 of gage studs on said support upon which the work-sheets are impaled by means of perforations in the side margins of the work-sheets, said sets of studs movable to carry the work-sheets simultaneously to the platen and position them relatively to the printing line on the platen.

40. In a typewriting machine, the combination with a revoluble platen, of a work-sheet support adjacent to the platen, and two sets of gage studs on said support upon 70 which work-sheets are impaled by means of perforations in the side margins of the work-sheets, to position the work-sheets relatively to the printing line on the platen, and means to coöperate with said gage studs to carry the work-sheets around the platen. 75

41. In a typewriting machine, the combination with a platen, of two sheet-engaging devices including members remote from the platen, for positioning perforated work-sheets relatively to the printing line on the 80 platen, said sheet-engaging devices consisting of sets of studs upon which the work-sheets are impaled by means of their perforations, and being movable to carry the sheets to the printing position. 85

42. In a typewriting machine, the combination with a work-sheet support, of a platen adjacent to said support, a set of impaling gage-studs, extending along said support, for positioning a perforated work-sheet with 90 reference to the printing line by means of perforations in the work-sheet, said studs being movable along said support to and from the platen, and line-spacing means for said platen. 95

43. In a typewriting machine, the combination with a revoluble platen, of sets of work-sheet impaling studs mounted for positioning perforated work-sheets with reference to the printing line, means to co-operate with said studs and said platen for carrying the collated sheets to printing position upon said platen, and line-spacing means for said platen. 100

44. In a typewriting machine, the combination with a revoluble platen, of a work-sheet support adjacent to the platen and arranged at the delivery side thereof, and sets of gage studs extending along said support upon which perforated work-sheets are impaled, said gage studs arranged to gage the work-sheets by means of their perforations 110 relatively to the printing line on the platen, endless flexible means to coöperate with said platen and said studs for carrying the collated sheets to printing position upon the platen, and thence away from the platen, and line-spacing means for said platen. 115

45. The combination with typewriting mechanism including a rotatable platen, of 120 means for assembling several work-sheets at different relative positions at line-space intervals or multiples thereof from each other, and passing with the sheets while maintaining the latter in their assembled relation 125 around said platen, so as to bring different lines of the several sheets in conjunction at the same time with the line to be typewritten on at the platen.

46. The combination with a rotatable 130

platens; of conveying means extending from said platen to a point some distance from the platen where work-sheets may be assembled thereon, said conveying means having attaching points located at line-space intervals as measured by said platen, so that the work-sheets may be variously positioned thereon, driving means for rotating said platen in the aggregate and at once many 10 line spaces, so as to bring the work-sheets positioned on said conveying means to said platen and around to the printing point, and line-space mechanism for driving said platen line-space intervals for writing on 15 successive lines on the work-sheets carried to said platen by said conveying means.

47. The combination with a rotatable platen, of conveying means extending from said platen to a point some distance from 20 said platen where work-sheets may be assembled thereon, said conveying means having attaching points located at line-space intervals as measured by said platen, so that the work-sheets may be variously positioned 25 thereon, driving means for rotating said platen in the aggregate and at once many line spaces so as to bring the work-sheets positioned on said conveying means to said platen and around to the printing point, and line-space mechanism for driving said platen 30 line-space intervals for writing on successive lines on the work-sheets carried to said platen by said conveying means, the driving ratio to said platen from said driving means 35 and said line-space mechanism being widely

different, so that similar movement on the one hand will produce a rapid rotation of many line spaces of said platen, and on the other hand will produce but a single line-space movement of said platen. 40

48. The combination with a platen, of spacing studs, and means for moving said studs from a position extraneous to the platen to a position around the platen, to carry therewith *en bloc* two or more perforated work-sheets collated thereon while extraneous to the platen. 45

49. In a typewriting machine, the combination of a pair of endless work-carrying bands upon which sheets may be collated in flat condition and carried to printing position, said bands having studs, and revolute means for engaging said studs to cause the bands to travel in register with each other. 50

50. In a typewriting machine, the combination of a pair of endless work-carrying bands upon which sheets may be collated in flat condition and carried to printing position, said bands having studs, and revolute 55 means for engaging said studs to cause the bands to travel in register with each other; said revolute means comprising a device extending from one band to the other and having means to mesh with said studs to control the registry of the bands. 60
